UNITED STATES PATENT OFFICE.

GEORGE ZINZEL, OF SCRANTON, PENNSYLVANIA.

TIME SWITCH.

Application filed February 17, 1922. Serial No. 537,225.

To all whom it may concern:

Be it known that I, GEORGE ZINZEL, a citizen of the United States, residing at Scranton, in the county of Lackawanna and State of Pennsylvania, have invented a new and useful Time Switch, of which the following is a specification.

This invention aims to provide a simple form of time controlled switch, whereby the lights in a building may be extinguished at any advance time, automatically, the construction of the device being such that a standard form of alarm clock mechanism may be employed to advantage.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in front elevation, a device constructed in accordance with the invention; Figure 2 is a rear elevation; Figure 3 is an elevation wherein the device is viewed edgewise; Figure 4 is a longitudinal section wherein parts appear in elevation; Figure 5 is a section on the line 5—5 of Figure 3, the line 4—4 in Figure 5 indicating the cutting plan on which Figure 4 is taken; Figure 6 is a section on the line 6—6 of Figure 5.

In carrying out the invention, there is provided a support, which, preferably, is in the form of a box-like frame 1, having a front opening 2 and a rear opening 3. The numeral 4 marks the casing of an alarm clock, of standard and known construction, the casing being located within the frame 1 and extending outwardly through the front opening of the frame, the casing being secured at 5, in any suitable way to the back of the frame 1. In view of the fact that an ordinary alarm clock mechanism may be used, the cost of the device may be cut down appreciably, it being necessary, merely for the manufacturer to use a simple alarm clock which may be purchased at trifling cost, as

distinguished from providing a specially made and expensive time mechanism.

In view of the fact that the clock is of known construction, the description of the mechanism of the clock may be shortened accordingly, and only such parts thereof are referred to as enter into combination with parts hereinafter described. The clock, as usual, comprises a main dial 6, the hour hand appearing at 7, and the minute hand at 17. The winding stem for the time train is shown at 8, and the setting stem for the time train at 9, these elements being prolonged rearwardly through the opening 3 in the back of the frame 1. The regulator is shown at 10 and is accessible through the opening 3.

The frame of the clock is shown at 11 and carries the alarm train, the alarm train being, in this invention, the actuating train whereby the switch, (hereinafter described) is actuated and controlled.

The operating train embodies a winding shaft 12, journaled in the frame 11. A gear 80 wheel 14 is loose on the winding shaft 12, but is connected thereto by a pawl and ratchet mechanism 15. The numeral 16 marks a driving spring, one end of which is secured to the clock frame 11, the other end of which is secured to the ratchet of the pawl and ratchet mechanism 15, in the usual way, the construction being such that the spring may be put under tension by rotating the winding shaft 12, the spring then reacting to drive the operating train.

The gear wheel 14 meshes with a pinion 18 carried by a shaft 19 journaled in the frame 11. A gear wheel 20 is mounted on the shaft 19 and meshes with a pinion 21 on a shaft 22 journaled in the frame 11, the shaft 22 carrying a star wheel 23 adapted to coact with a rocker 24 on a shaft 25 journaled in the frame 11, the shaft 25 carrying an arm 26 provided with a forwardly extended projection 27. The arm 26 is the part which carries the striker in an alarm clock, but, in the present invention, the striker is removed, and the arm 26 is bent to form the projection 27, it being necessary, therefore, to make merely a minor change in the mechanism of the alarm clock to adapt it to the use contemplated in this invention.

The shaft 25 carries a detent arm 28 located in the path of a spring latch 29, one end of which is secured at 30 to the clock frame 11. The setting shaft for the operat-

- ing train is denoted by the numeral 31 and is mounted for rotation in the frame 11, the shaft projecting rearwardly through the opening 3 in the frame 1. At its forward 5 end, the setting shaft 31 carries the usual hand 32 adapted to cooperate with a supplemental dial 33 inscribed on the main dial 6. At its forward end, the setting shaft 31 carries a disk 75, from which a radial finger 10 34 projects. The finger 34 is adapted to cooperate with a cam notch 35, formed in the outer end of a collar 36 secured to a gear wheel 37, mounted for rotation upon the setting shaft 31 and mounted to slide 15 longitudinally of the said shaft, the angle of the spring latch 29 being slidable on the shaft 31, and the hub of the gear wheel 37 bearing against the angle of the spring latch 29.
- 20 The clock mechanism includes the usual time train which actuates the hands 7 and 17. It is not necessary to show the entire time train, since no novelty is claimed therefor. Let it suffice to say that the time train 25 comprises a pinion 38 meshing with the gear wheel 37, and the gear wheel 39 whereby rotation is imparted to the pinion 38.
- The device forming the subject matter of this invention may be resolved logically into 30 two constituent mechanisms to wit, a time-controlled operating train, and a switch mechanism. In view of the foregoing, and since the operating train is of known and standard construction, the description will 35 be suspended at this place, to trace out the functions of the various parts of the operating train.
- The setting shaft 31 is rotated until the hand 32, cooperating with the supplemental 40 dial 33, marks the time at which the lights are to be extinguished, the finger 34 resting against the end of the collar 36 in spaced relation to the notch 35, circumferentially of the collar, the collar 36 and the gear 45 wheel 37 being slideable rearwardly on the shaft 31, the hub of the gear wheel 37 springing the latch 29 rearwardly, until the latch engages the detent arm 28 and holds the operating train against movement, responsive 50 to the driving spring 16. When the time train has moved to a predetermined position, represented by the location of the hands 7 and 17 on the main dial 6, and by the position of the hand 32 on the supplemental dial 33, the gear wheel 39 and the 55 pinion 38 of the time train will have rotated the collar 36, through the instrumentality of the gear wheel 37 until the notch 35 in the collar is alined with the finger 34 on the setting shaft 31. Thereupon, the latch 29 springs forwardly, and is disengaged from the detent arm 28, the gear wheel 37 and the collar 36 sliding outwardly on the shaft 31, the finger being received in the 60 notch 35 in the collar. The operating train 65 now is set free, and motion is transmitted from the spring 16 to the gear wheel 14, the pinion 18, the shaft 19, the gear wheel 20, the pinion 21, the shaft 22, the star wheel 23, and thence to the rocker 24 on the shaft 70 25, the rocker cooperating with the star wheel, the shaft 25, together with the arm 26 and its projection 27, being oscillated. The operating train will continue to run until a part 49, shown best in Figure 5, and hereinafter described, is raised and interposed in the path of the projection 27 on the arm 26.
- Passing to a description of the switch mechanism, it may be stated that a block 80 or bracket 40 is mounted on one side portion of the frame 1. A guide 41 extends upwardly along the bracket 40 and is provided with a flange 42, connected by a pivot element 43 with the bracket, the construction being such that the guide can swing on the bracket 40 in a direction parallel to the cutting plane in Figure 5. The numeral 44 designates a retractile spring, one end of which is secured to the bracket 40, the other end of the spring being secured to the guide 41 above the pivotal mounting 43 of the guide. Swinging movement of the guide 41, responsive to the spring 44, is limited by a stop pin 45 which, being mounted in 95 the bracket 40 is adapted to engage the outer edge of the flange 42 as shown clearly in Figure 5. The guide 41 extends upwardly into the clock casing 4, through an opening 46 fashioned in the clock casing. A rack 100 bar 47 is mounted for right line reciprocation in the guide 41, the guide being cut away, as at 48 in Figure 5, so that the gear wheel 14 of the operating train may mesh with the rack bar. Adjacent to its upper 105 end, the rack bar 47 carries the part of projection 49, hereinbefore alluded to and adapted to coact with the projection 27 of the arm 26 which is carried by the shaft 25. On its outer side, the guide 41 is cut away, as at 50 for the reception of an operating rod 51, held on the rack bar 47 by a lock nut 52, or otherwise. The operating rod 51 is provided with a knob 53, disposed outside of the box-like frame 1, the rod 51 being adapted to move vertically in registering slots 54 formed in the side of the frame 1 and in a plate 55 which is attached thereto, the element 55 serving as a wear plate for the knob 53.
- To the bottom portion of the box-like frame 1, an insulating block 56 is secured. A switch member 57 is superposed on the block 56, as is a second switch member 60. A switch lever 58 is pivoted at 59 to the switch member 57 and is adapted to be moved downwardly and upwardly, into and out of engagement with the switch member 60, as indicated in Figure 5. Securing elements 61 unite the switch members 57 and 110 115 120 125 130

60 with the block 61, and connect the block to the bottom portion of the box-like frame 1, the securing elements passing through insulating thimbles 62 carried by the bottom 5 portion of the frame 1. On the lower ends of the securing elements, binding nuts 63 or their equivalents are mounted, the binding nuts being adapted to hold the conductors 64 of a lighting circuit. An insulating 10 link 65 is connected by a pivot element 66 to the free end of the switch lever 58, a pivot element 67 connecting the link 65 to the lower end of the rack bar 47. A retractile spring 68 is shown, the lower end of this 15 spring being mounted on the pivot element 67, and the upper end of the spring being anchored, as at 69, to the bracket or block 40.

Supposing that the operating train, including the gear wheel 14, is at rest, the 20 guide 41 may be swung on its pivotal mounting 42, to disengage the rack bar 47 from the gear wheel 14, the guide being swung, as aforesaid, and the rack bar being carried downwardly, through the instrumentality of 25 the operating rod 51 and the knob 53 thereon, the spring 44 swinging the guide 42, and the rack bar 47, until the rack bar meshes again with the gear wheel 14 as shown in Figure 5, the rod 51 being at the 30 lower end of the slot 54, as shown in solid line in Figure 5. When the rack bar 47 is moved downwardly, the spring 68 will be put under tension and the link 65 will swing the switch lever 58 downwardly until the 35 switch lever cooperates with the switch member 60, the circuit of which the conductors 64 constitute a part being closed and the lamps in the said circuit being lighted. The parts will be held in the positions shown 40 in solid line in Figure 5, because the rack bar 47 is held by the spring 44 in engagement with the gear wheel 14, the operating train, of which the gear wheel 14 constitutes a part, being at rest.

The way in which the operating train is 45 set free, has been described hereinbefore, and it may be remarked briefly at this point that when the hands 7 and 17 of the clock mark the predetermined time, the operating 50 train, including the gear wheel 14 will be put into motion, the rack bar 47 being raised, and the switch lever 58 being moved out of engagement with the switch member 60 whereupon the lighting circuit will be 55 opened. The function of the spring 68 is to aid the rack bar 47 in its upward movement, thereby taking the large portion of the work off the driving spring 16 which actuates the operating train. The rack bar 60 47 moves upwardly, responsive to the gear wheel 14, until the projection 49 on the rack bar engages the projection 27 on the arm 26 of the shaft 25 whereupon motion in the operating train will cease, the rack bar 47 65 no longer moving upwardly.

Although in the foregoing description, it has been pointed out that the switch lever 58 is moved to open position with respect to the switch member 60, by the action of the gear wheel 14 on the rack bar 47, it will 70 be obvious that the circuit may be opened by hand, the rack bar 47 being moved out of mesh with the gear wheel 14, and being elevated, by means of the rod 51 and the knob 53.

Having thus described the invention, what is claimed is:

1. In a device of the class described, an operating train comprising a gear wheel; spring means for operating the train; time-controlled mechanism for holding the train releasably against movement responsive to the spring means; a rack bar; means for mounting the rack bar for transverse swinging movement, into an out of engagement with the gear wheel; means under the control of an operator for imparting transverse swinging movement to the rack bar at any time to release it from engagement with the gear wheel; a switch; and means for connecting the switch with the rack bar.

2. In a device of the class described, an operating train comprising a gear wheel; spring means for operating the train; time-controlled mechanism for holding the train releasably against movement responsive to the spring means; a rack bar; means for mounting the rack bar for transverse swinging movement, into and out of engagement with the gear wheel; spring means for holding the rack bar in mesh with the gear wheel; means under the control of an operator for moving the rack bar at any time to release it from engagement with the gear wheel out of engagement with the gear wheel; a switch; and means for connecting the switch operatively with the rack bar.

3. In a device of the class described, an operating train comprising a gear wheel; spring means for operating the train; time-controlled mechanism for holding the train releasably against movement responsive to the spring means; a rack bar; means for mounting the rack bar for transverse swinging movement, into and out of engagement with the gear wheel; means under the control of an operator for imparting transverse swinging movement to the rack bar at any time to release it from engagement with the gear wheel; a switch; means for connecting the switch operatively with the rack bar; and spring means cooperating with the rack bar to assist in the movement of the rack bar when the rack bar is in mesh with the gear wheel.

4. In a device of the class described, a support; a rack bar; means for mounting the rack bar on the support for swinging movement and for longitudinal movement; spring means for imparting longitudinal

- movement to the rack bar; spring means for imparting swinging movement to the rack bar in one direction; means under the control of an operator for imparting swinging movement to the rack bar in an opposite direction at any time to release it from engagement with the gear wheel; a switch on the support; and means for connecting the switch operatively with the rack bar.
- 10 5. In a device of the class described, a support; a guide mounted to swing on the support; spring means for swinging the guide in one direction; means under the control of an operator for swinging the guide in an opposite direction at any time to release it from engagement with the gear wheel; a rack bar mounted for reciprocation in the guide; a switch on the support; and means for connecting the switch operatively with the rack bar.
- 15 6. In a device of the class described, a support; a guide mounted to swing on the support; spring means for swinging the guide in one direction; means under the control of an operator for swinging the guide in an opposite direction at any time to release it from engagement with the gear wheel; a rack bar mounted for reciprocation
- in the guide; a switch; means for connecting the switch to the rack bar; and spring means for assisting in the movement of the rack bar when the rack bar disposes the switch in open position.
7. In a device of the class described, an operating train comprising a gear wheel and a shaft mounted for oscillation; spring means for operating the train; an arm on the shaft; time-controlled mechanism for holding the train releasably against movement responsive to the spring means; a rack bar; means for mounting the rack bar for transverse swinging movement into and out of mesh with the gear wheel; means for imparting transverse swinging movement to the rack bar; means on the rack bar and cooperating with the arm to stop the movement of the train responsive to the spring means; a switch; and mechanism for connecting the switch with the rack bar.
- 10 15 20 25 30 35 40 45 50
- In testimony that I claim the foregoing as my own, I have hereto affixed my signature in the presence of two witnesses.
- GEORGE ZINZEL.
